PACKAGE AND METHOD OF PRODUCING
SAME

Robert A. Ramsdell, Syosset, N. Y., assignor, by
mesme assignments, to E. I. du Pont de Ne-
mours & Company, Wilmington, Del., a cor-
poration of Delaware

Application June 21, 1935, Serial No. 27,825

4 Claims. (Cl. 117—1)

This invention will be described with particu-
lar reference to crepe twisting of silk and rayon;
however, it is to be understood that the scope
of the invention includes the production of all
5 types of high twist yarn having such weight or
denier and such a high degree of twist that the
twist must necessarily be imparted thereto by
means of throwing machines commonly referred
to as uptwisters or silk spinners.

10 Heretofore the crepe twisting of silk and rayon
has involved the following essential procedure:

The silk or rayon, in the form of skeins, was
treated, for example by immersion, with a suit-
able dope. This dope usually comprises an oil
15 finish, an adhesive and a fugitive dye or tint.
The adhesive, consisting ordinarily of gelatin,
functions to hold the high twist in the yarn and
prevents the same from becoming lively after
the twist has been set. The oil lubricates and
20 softens the yarn to protect the same in subse-
quent winding and throwing operations. The dye
or tint serves to identify the yarn during subse-
quent twisting, winding and weaving operations.
The treated yarn was then wound onto small
25 spools made of wood or fiber composition with
relatively large barrels and small heads. Only a
small amount of yarn could be contained on such
a spool, hereinafter to be referred to as "throw-
ing spool", from which it was to be crepe twisted,
30 for reasons which will appear hereinafter. In
the handling of 100 denier yarn, not more than
1 to 3 ounces could be wound on a throwing spool.
These spools were then mounted on suitable ver-
tical spindles capable of revolving at high speeds,
35 such, as for example, 9,000 to 11,000 R. P. M.
The spools of yarn were revolved either in a
clockwise or counter-clockwise direction, depend-
ing upon the direction of twist desired in the
yarn. The yarn is drawn up and away from the
40 revolving spool at a constant speed and wound up
on another spool or take-up bobbin which is
sometimes referred to as a steaming spool.

The type of machine used to impart a high
twist to a fine denier thread in the manner above
45 described is that above referred to as an up-twist-
er or silk spinner. It has been found necessary
to use this type of machine for fine denier yarn
when a high degree of twist is to be imparted
thereto. By operating in this manner less ten-
50 sion and frictional resistance are placed on the
yarn than in other types of twisting apparatus.

A flyer or yarn guide is rotatably positioned on
the top of the spindle of an up-twister for the
purpose of guiding the yarn from the throwing
55 spool to the take-up bobbin and controlling the

tension and the ballooning of the yarn. This
flyer ordinarily consists of a horizontally disposed
wire having an eye at one end thereof which ex-
tends beyond the edge of the top head of the
throwing spool as it is important that the yarn 5
balloon around the periphery of the head of
the spool without contacting therewith to prevent
degradation of the yarn.

The throwing spools as known heretofore were
necessarily made with comparatively large bar- 10
rels and were wound with relatively few layers
of yarn. The spool was wound with relatively
few layers of yarn so as to maintain a sufficiently
small diameter to prevent excessive peripheral
or centrifugal forces from being transmitted to 15
the yarn at the high rotational speeds of the
spool. The barrels are made comparatively large
to prevent the thread from being drawn over the
head of the spool without ballooning, or from
ballooning at a sharp angle from the spool. 20

The production of artificial thread has been
improved to the point where it is no longer nec-
essary to process the same in skein form. The 25
artificial thread is formed by extrusion of a liq-
uid through a spinneret and collected in a cen-
trifugal bucket or on a bobbin. The artificial
thread, so collected, is then processed by wash-
ing, desulfuring, bleaching and drying in the form 30
of package in which it is originally collected, or,
in the case of bobbins, a package formed from 35
the original by rewinding and twisting. The
form of package in which the artificial thread
is processed, as above-described, will be herein-
after referred to as the "original package". It
has been found that the artificial silk can also be 40
treated with a suitable creping dope in its origi-
nal package form, thus eliminating the opera-
tion of first winding the same into the form of
skeins. Consequently, the transportation of arti- 45
ficial yarn, in the form of skeins, from the pro-
ducer thereof to the throwster, would involve
an otherwise unnecessary step of first skeining
the yarn. To transport the yarn in the original
package form is undesirable and impractical. 50

It has been suggested to wind the processed 45
and doped yarn directly from the original pack-
age to a throwing spool and transport the yarn
from the producer to the throwster in this form,
thus eliminating the skeining operation. This has
been found to be entirely impractical by reason 50
of the comparatively large percentage of space
and weight taken up by the throwing spools.
Furthermore, the empty throwing spools would
again have to be returned to the yarn producer.

In an attempt to overcome this last-mentioned 55

difficulty it has been suggested to first wind the yarn from the dope-treated original package onto a substantially rigid paper or fiber core in the conventional "cone" form of package, the yarn transported in the form of cone packages to the throwster, and then rewound onto a throwing spool. This procedure is obviously little better than first skeining the same and transporting the yarn in skein form. In this connection it was 5 well recognized by the art that a cone may be used directly in the so-called down-twister type of machine in which the cone remains stationary and the take-up bobbin is rotated. In an up-twister type of machine, on the other hand, the 10 cone would be rotated at such a high rate of speed that the layers of thread would telescope and be thrown in large bunches from the cone by the centrifugal force.

The applicant has now found that, contrary 20 to accepted practice, a yarn package which may be economically transported and which may be used directly on the throwing spindle without first rewinding the yarn onto a throwing spool, can be wound from the original package.

25 It is therefore an object of this invention to provide an improved process for the production of crepe twisted yarn from artificial thread.

It is another object of this invention to provide a suitable package of artificial thread which has 30 been dope-treated for high twist, such as crepe twist, and which can be economically produced and transported to a distant plant for direct use on the spindle of an up-twister.

Other objects of the invention will appear hereinafter.

The objects of my invention are achieved, in general, by processing an original package of artificial silk including the treatment thereof with a suitable creping dope, then winding the treated 40 yarn on a substantially rigid, light-weight core by means of a precision winding machine, such as, for example, a machine of the type manufactured by the Universal Winding Machine Corporation and commonly referred to in the art 45 as a Universal Winder. The yarn is precision-wound to form a relatively large package, the total weight of which is at least five times the weight of the core. The package is then transported to a throwing plant where it is directly 50 positioned on a throwing spindle of an up-twister and a high twist imparted to the yarn.

The objects and purposes of the invention will be more clearly apparent by reference to the following detailed description taken in connection 55 with the accompanying illustrations of certain specific embodiments thereof, it being understood that the invention is not limited thereto.

In the drawing:

Fig. 1 is a vertical cross-sectional view of a 60 yarn package which may be directly mounted on the spindle of an up-twister.

Fig. 2 is a vertical cross-sectional view of a modified form of yarn package.

Fig. 3 is a vertical cross-sectional view showing 65 an adapter which may be interposed between a suitable yarn package and a spindle of an up-twister.

Fig. 4 is a vertical cross-sectional view showing a 70 yarn package and adapter mounted on the spindle of an up-twister; and

Fig. 5 is a vertical cross-sectional view showing a conventional throwing spool.

The yarn package illustrated in Fig. 1 of the drawing consists of a rigid, light-weight core 11 75 of paper, paste-board, card-board, fiber, or the

like, and yarn 12 tightly wound thereabout. This core is preferably of uniform cross-section throughout the length thereof so as to produce a package of yarn having substantially cylindrical contour, thus preventing bunches or layers of 5 yarn from shifting on the package or "sloughing off" due to centrifugal force, however, a slightly conical core may be used without objectionable shifting of the thread.

The yarn package may contain up to $\frac{3}{4}$ pound 10 of yarn and may be as much as $2\frac{1}{2}$ inches in diameter. I prefer however a package containing 4 to 5 ounces of yarn and having an outside diameter of about $2\frac{1}{4}$ inches. The package may vary in length but should be short enough to be 15 accommodated on the throwing machines without alteration. The inside diameter of the core 11 is preferably about one inch although considerable variation in this dimension is permissible. The core should comprise no more than about 20 20% of the total weight of the package, and normally will comprise about 10 to 18% of the total weight thereof.

The core 11 is wound with the yarn 12 directly 25 from the original package. The winding operation is preferably carried out on a precision winding machine of the Universal type. In the winding of the package the stroke of the traverse is progressively shortened so as to form the package with tapered ends, the taper being about 30 .80 to 75° . The yarn is preferably tightly wound without about 4 turns around the package per traverse stroke whereby to obtain a compact package of yarn requiring no head to support the same despite the high rotational speed to 35 which it is to be submitted.

The package of Fig. 1 has the additional advantage that it may be used to produce either right- or left-hand twisted crepe thread by merely reversing the end of the package which is 40 first placed on the spindle. In the use of throwing spools as known heretofore it was necessary to wind the yarn thereon in a specified direction to make it suitable for production of left-hand twist crepe and in the other direction to make 45 it suitable for production of right-hand twist crepe by reason of the fact that throwing spools must always be positioned on a spindle with the same end down. Therefore, in accordance with the present invention, the same package 50 can be used for either right- or left-hand twist yarn.

Fig. 2 shows a modified form of a thread package having a rigid, light-weight core 13 comprising a cylindrical hollow barrel 13 and a head 55 or flange 33. The flange 33 will prevent sloughing off of the thread 14 from one end of the package and the thread may be wound against the flange so that a larger amount of thread 60 may be contained thereon. This form of package, however, has the disadvantage that only left- or right-hand twist crepe thread may be produced therefrom, depending upon the direction in which the thread is wound on the core.

Referring to Figs. 3 and 4 of the drawing, 65 15 designates a throwing spindle of an up-twister, 16 designates an adapter which may be mounted on the spindle 15 to receive the yarn package of Figs. 1 or 2. The adapter 16 consists of a solid barrel 36, a head 22 and a plurality of leaf 70 springs 17. The adapter has a sufficiently small diameter to permit the core 11 (or 13) to easily slide thereover. When the package is positioned on the adapter the springs 17 are compressed to hold the package firmly in place thereon. The 75

adapter 16 is provided with any desired driving engagement with the spindle such as, for example, the tapered fit shown in Figs. 3 and 4.

The form of adapter described is particularly desirable since it can be easily and quickly formed from conventional throwing spools as shown in Fig. 5 of the drawing. The throwing spool barrel 24 is merely cut down to the desired diameter, for example, by turning on a 10 lathe, and the top head 23 removed therefrom. The barrel is then provided with suitable holding means such as the leaf springs 17.

Obviously, the adapter may be omitted, if desired, by forming the core of such diameter that 15 it may be directly mounted on the spindle of an up-twister.

After the yarn package is positioned on the spindle 15, as shown in Fig. 4, the projecting end of the spindle is provided with a flyer 26 by 20 rotatably positioning the flyer bearing 18 on the spindle in a known manner. The yarn, which has only sufficient twist to prevent it from opening, is passed through one eye 21 of the flyer and then to a take-up bobbin (not shown). The 25 spindle is now rotated at a high speed, for example, 10,000 R. P. M., and the yarn wound up on a take-up bobbin or steaming spool at the rate of 250 inches per minute whereby a twist of 40 turns per inch is imparted to the thread, 30 assuming no contraction in length.

The following example will serve to illustrate more clearly the steps of producing crepe twist thread in accordance with the present invention, it being understood that the invention is not to 35 be limited to the specific details set forth:

Bucket cakes of 100 denier-40 filament yarn spun with a left twist of 4 turns per inch, and which have been washed, desulfured, bleached and dried in the original package form, for example, in accordance with the process described 40 in the copending application, Serial No. 683,896, to J. S. Fonda et al., are subjected to a soaking operation which comprises immersing the processed package for about one-half hour in a bath 45 composed of 27 pounds sulfonated olive oil, 4 pounds gelatin, 50 gallons of water, and 1/2 to 2 grams of fugitive dye per liter of solution, depending upon the depth of color desired, which is maintained at a temperature of 120°-130° F. 50 Thereafter, the packages are centrifugally wrung by rotating the same about their own axes for about 3 minutes at a speed of about 7,000 R. P. M., and dried. The dried packages of yarn, after humidification or conditioning, in a known 55 manner, are directly wound on the cylindrical core above described by means of a Universal precision winding machine to form a package containing about 1/4 pound of yarn, and of the general shape illustrated by Fig. 1 of the drawing. The package is then transported to a throwing mill where it is mounted on the throwing spindle of an up-twister and a high twist 60 imparted thereto as above set forth.

Any desired doping or tinting solution may 65 be used to impart the desired characteristics to the yarn. Furthermore, the doping or tinting solution may be applied to the yarn in any desired manner and at any suitable point in the process.

70 The comparatively large size of the package produced in accordance with this invention will permit a long period of twisting per spindle without changing packages. In spite of the large change in diameter of the package from the beginning to the end of the twisting thereof, it

has been found that the thread tension does not vary greatly and that a substantially uniformly twisted crepe thread is produced. This is partially due to the fact that the end of the package does not require a head around which the 5 yarn must be drawn as is the case with throwing spools. The radius of the flyer need not be so large as to over-hang the edge of the outer diameter of the yarn. Therefore, the centrifugal force of the yarn as it is forced against the flyer 10 or the radius of the balloon of the yarn is not of such magnitude as to injure the yarn.

The light-weight paper or fiber core used in accordance with the present invention is of cheap construction and therefore is suitable for one-way shipment.

The direct winding of the yarn onto the core from the original package eliminates at least one winding operation from previously known methods.

In accordance with the present invention a larger quantity of artificial thread can be mounted on a spindle for twisting without increased power consumption.

A relatively large package of yarn can be prepared and wound with more perfect wind than is possible with the use of headed spools such as previously used in the crepe twisting of artificial silk, thus greatly reducing difficulties in throwing and the time given by the attendant per pound 25 of crepe produced.

By eliminating the skein processing of artificial thread the yarn is much less degraded, and contains fewer knots, broken filaments, fluff balls, and the like.

The invention is applicable to silk or any type of artificial thread, such as regenerated cellulose thread produced by the viscose or cuprammonium process, cellulose ester or ether thread such as cellulose acetate, benzyl cellulose, glycol cellulose threads, and the like.

Many changes and modifications may be made in the present invention without departing from the nature and spirit thereof. It is therefore to be understood that the invention is not to be limited to specific steps and modifications above described except as set forth in the appended claims.

I claim:

1. In a process for the production of crepe twisted artificial thread from original packages of thread produced in the filament forming operation and which have been purified, dried, doped and have a preliminary twist imparted thereto, the steps comprising precision-winding said thread from the original package onto a light-weight, headless core, to form a package which may be mounted on and from which the thread may be directly twisted by means of an up-twister, said package being economically transportable for long distances, and crepe twisting said thread directly therefrom.

2. In a process for the production of crepe twisted artificial thread from original packages of thread produced in the filament forming operation and which have been purified, dried, doped and have a preliminary twist imparted thereto, the steps comprising precision-winding said thread from the original package onto a light-weight, headless core, to form a package which may be mounted on and from which the thread may be directly twisted by means of an up-twister, said package being economically transportable for long distances, positioning said re- 70 75

wound package on a spindle of an up-twister and crepe twisting said thread directly therefrom.

3. In a process for the production of crepe twisted artificial thread from original packages of thread produced in the filament forming operation and which have been purified, dried, doped and have a preliminary twist imparted thereto, the steps comprising precision-winding said thread from the original package onto a light-weight, headless core, to form a package containing approximately 4 to 12 ounces of thread and which may be mounted on and from which the thread may be directly twisted by means of an up-twister, said package being economically transportable for long distances, and crepe twisting said thread directly therefrom.

4. In a process for the production of crepe twisted artificial thread from original packages of thread produced in the filament forming operation and which have been purified, dried, doped and have a preliminary twist imparted thereto, the steps comprising precision-winding said thread from the original package onto a light-weight, headless core, to form a package which may be mounted on and from which the thread may be directly twisted by means of an up-twister, said package being economically transportable for long distances, said core weighing not in excess of 20% of said package, and crepe twisting directly from said rewound package.

ROBERT A. RAMSDELL.
